SLIDING WINDOW CONSTRUCTION

John F. Levan, Elkhart, Ind., assignor to Excel
 Curtain Company, Inc., Elkhart, Ind., a corporation of Indiana

Application September 10, 1940, Serial No. 356,197

1 Claim. (Cl. 189—64)

This invention relates to sliding sash, particularly for vehicles, as buses, and has for its object a weather strip construction, which is free of moisture absorbent material, so that it remains the same under all weather conditions, as it is not affected by moisture, and hence is easily and uniformly operable under all conditions, and further holds the sash from developing looseness and rattling.

The invention consists in the novel features and in the combinations and constructions hereinafter set forth and claimed.

In describing this invention, reference is had to the accompanying drawing in which like characters designate corresponding parts in all the views.

Figure 1 is an isometric view of this window construction, the contiguous portion of the vehicle body being also shown.

Figure 2 is an enlarged sectional view on line 2—2, Figure 1.

Figure 3 is a fragmentary edge view of the sash.

1 designates the window frame suitably mounted in a window opening of a car body 2, the frame being formed with an inwardly facing sash guide or sash receiving channel. The frame may be of any suitable construction to provide an inwardly extending guide flange 3 which, in the illustrated embodiment of the invention, forms one side of the sash guide channel 4.

5 designates a sliding sash, the frame of which is usually formed up of sheet metal to provide a channel 6 at the edge of the sash. The window here shown is provided with a stationary glass panel 7 at one end of the window frame and the sliding sash 5 slides horizontally laterally into and out of closed position, and laps the stationary panel 7. The flange 3 and channel 4 of the frame are provided not only in the upper and lower rails thereof but also in the end or upright rail of the frame, and the channel 6 of the sash 5 is formed also in the upper and lower horizontal rail of the sash and upright end rail of the sash. The sash 5 is arranged with the channel 6 astride the flange 3 of the frame with one side wall or flange 8 of the channel 6 lapsing the outer side of the flange 3 with the other side wall or flange 9 of the channel 6 spaced from the flange 3 and extending into the channel 4 of the frame.

The non-absorbent weather strip means for holding the sash against undue looseness comprises a metal spring-pressed strip or shoe 10 arranged in the channel 6 of the sash 5, it being

movable with the sash and interposed between the flange 9 of the channel 6 of the sash and the inner face of the flange 3 of the window frame. It is thrust against said flange 3 by suitable means, as springs 11. The springs here shown are leaf, or bowed springs secured between their ends, as by rivets 12 to the strip 10 and having their ends thrusting against the inner face of the flange 9 of the sash, as at 13. The portion 5 of the flange 8 of the sash along the upright end of the sash moves into and out of lapping engagement with the portion 3a of the flange 3 of the frame at one end of the frame, and likewise the portion or strip 10 in the upright or end rail 5a of the sash moves into and out of engagement with the flange portion 3a during complete closing and partial or complete opening of the sash. The channel is preferably provided with a lining 14 of a non-absorbent material extending at least between the confronting surfaces of the flanges 3 and 8.

Preferably, the outer edge of the weather strip 10 is provided with an angular flange 15 at the edge of the sash forming a partial shield for the 10 apex portions of the springs 11. The corner at 16 between the body of the strip 10 and the flange 15 is beveled sufficiently in the portion thereof at the end edge of the sash to guide the edge of the portion 3a of the flange 3 between the strip 10 and the flange 8 when the sash 5 is being closed. The strip 10 is practically coextensive in length with the upper, lower and end rails of the sash and is spring-compressed throughout its length. In order to secure the strip 10 to the 15 sash 5, one or more of the bowed springs may be secured at one end to the sash 5 or the flange 9 thereof, as by fastening members or rivets 17.

The sash is provided with a suitable handle 18 which is here shown as provided with a suitable 20 latch 19 for coacting with a keeper plate 20 on the frame 1, when the sash is closed. When the sash is closed, it is sealed throughout its entire edge by the weather strip 10 being thrust by the springs 11 in one direction against the inner face of the flange 3 and the flange 8 being thrust in the opposite direction toward the outer face of the flange 3 by the spring 11, and as there is no felt or moisture absorbent material to swell and otherwise change its condition, and render the 25 opening and closing of the sash difficult, this sash works uniformly under all conditions.

What I claim is:

In a sliding window construction, a window frame provided with an inwardly extending sash guide flange, and a sliding sash mounted in the

frame and formed with a channel at its edge arranged astride said flange with one side wall of the channel lapping the outer side of the flange and a space between the inner side of the flange and the other side wall of the channel, and a spring-pressed, non-absorbent weather strip located in the channel and movable with the sash, said strip being coextensive in length with

said channel and thrusting against the inner side of said flange, whereby the engaging of one side wall of the channel and of the weather strip with the outer and inner faces respectively of said flange constitutes the only guiding of the sash with the frame.

JOHN F. LEVAN.
